UNITED STATES PATENT OFFICE.

OLIVER W. BARRICK AND JOSEPH E. SPEICHER, OF ALTOONA, PENNSYLVANIA.

AUTOMOBILE TOY.

1,269,250.

Specification of Letters Patent. Patented June 11, 1918.

Application filed September 29, 1917. Serial No. 193,853.

To all whom it may concern:

Be it known that we, OLIVER W. BARRICK and JOSEPH E. SPEICHER, citizens of the United States, residing at Altoona, in the county of Blair and State of Pennsylvania, have invented certain new and useful Improvement in Automobile Toys, of which the following is a specification.

This invention relates to improvements 10 in automobile toys, and has for its primary object improved means for propelling the toy in a forward and backward direction through the action of a spiral spring used as the power element for propelling the toy, 15 together with a reversing gear device which is designed to be operated by the power spring.

Another object of this device is to provide an improved reversing power device where- 20 by the direction of the toy is automatically reversed with sufficient power stored in the driving spring to return the toy to its original starting point.

With these and other objects in view which 25 will become more readily apparent as the nature of the invention is more fully brought out, the invention consists in the novel construction, combination, and arrangement of parts hereinafter more fully 30 described, illustrated and claimed.

The essential features of the invention involved in carrying out the objects above stated, are necessarily susceptible to some structural modification without departing 35 from the spirit or scope of the invention, but a preferred and practical embodiment there- of is shown in the accompanying drawings, in which—

Figure 1 is a plan view of the toy embody- 40 ing the present invention, portions thereof being broken away to more clearly illustrate the gear arrangement.

Fig. 2 is a side elevation of the present invention.

Fig. 3 is a sectional view taken on the line 4—4 of Fig. 1.

Fig. 4 is a detail view of the spiral driv- 50 ing spring showing its restricted side motion which facilitates the operation of the revers- ing gear.

Fig. 5 is a detail view showing how the end of the driving shaft opposite the wind- ing key is mounted.

Similar reference numerals refer to simi-

lar parts throughout the several figures of 51 the drawings.

In carrying out this invention we prefer to use a toy automobile, designated in its entirety by the numeral 10, and consisting essentially of a body 11, wheels and axles 60 12, wind shield 13, and a steering gear 14.

The driving element consists essentially of a spiral spring 15, having one end thereof fixed to a frame 16, while the other end is attached to the driving shaft 17. Driving 65 tension on the spring 15 is provided through a wing nut 18, which is rigidly attached to the shaft 17. For the purpose of holding the tension of the spring 15 there is provided a pawl and ratchet 19, the pawl being ful- 70 crumed on the frame at 20 as shown in Fig. 1 of the drawings.

For the purpose of driving the car in a forward direction there is provided a train of gears which consists essentially of two 75 spur gears, 21 and 22, the former being carried by the drive shaft 17 while the latter is positioned on the rear driving axle 23. It will be quite obvious from this construc- 80 tion that the rotation of shaft 17 will like- wise impart rotation to the driving axle 23 and the toy will move forward as designed.

For the purpose of providing means for operating the toy in a reverse direction there is provided a train of gears designated by 85 the numeral 24, which consists of a gear 25 secured to the rear axle 23, an idler gear 26 and a power gear 27 secured to the power shaft 17. The idler gear 26 is introduced for the purpose of changing the direction of 90 motion of the toy.

From Fig. 1 it will be observed that the gear 27 must mesh with gear 26 before motion in the reverse direction can be obtained and for the purpose of causing these gears 95 to mesh there is provided a cage 28 which is designed to cause a restrictive longitudinal movement of the spiral driving spring 15 as well as a partially restricted motion of the spring in a vertical plane.

The vertical movement of said spring as shown in Fig. 4 of the drawings actuates or shifts a pin 29, which is designed to move in suitable guides 30, and carries a pinion releasing element 31, which is adapted to hold the gear 27 out of mesh with gear 26 until the point 32 of the said element 31 105 clears the periphery of the locking disk 33,

at which time helical spring 34 asserts itself and pushes the shaft 17 transversely of the body 10, disengaging the forward driving gears 21 and 22 and causing the gear 27 5 to engage with the idler gear 26, these gears to reverse the motion of the toy.

From the foregoing it will be apparent that the shifting of the gears from a forward driving to a rearward driving posi-

10 tion is performed automatically by the expansion of the power spring as it unwinds, to thus bring the toy back to the operator. And, after the force of the driving spring has been spent by the forward and backward 15 motion of the toy, it becomes necessary to again rewind the spiral spring. This may be accomplished by turning the wing nut 18, whereby the said spring will be contracted sufficiently to permit the pin 29 to 20 fall and enable the nose 32 of the locking element 31 to engage with the disk 33 as shown in Fig. 3 of the drawings. This latter action, namely, the resetting of the shaft 17, involves the manual shifting of 25 said shaft so that the gears 26 and 27 are moved out of mesh, and the gears 21 and 22 are again intermeshed. As will be observed from Fig. 1, also Fig. 5, this manual shifting of the shaft 17 may be readily accom- 30 plished by finger pressure exerted on the exposed end of the shaft 17 which projects beyond the bracket 35. In connection with this feature of the invention it may be observed that the end of the shaft 17 opposite 35 the wing nut 18 is journaled in the side wall 36 of the toy and also in the bracket 35 which is spaced therefrom, and one end of said shaft projects beyond the bracket to provide a finger engaging portion for the 40 purpose previously referred to. Furthermore, as will be observed from Fig. 5, to limit the longitudinal movement of the shaft 17, the same is provided or fitted in the space between the bracket 35 and frame 45 of said wall 36 with a suitable stop collar or flange, or its equivalent 17^a. Obviously then, the limit of longitudinal movement of the shaft 17 is equal to the distance between the frame, and the bracket.

50 Without further description and elaboration it is thought that the many advantages of the herein described toy will be readily apparent and what we claim and desire to be secured by Letters Patent is—

55 1. A toy automobile including a body, wheels designed to carry the body, power means for propelling the toy in a forward direction, direction reversing means actuated by the power driving element, a train 60 of gears for transmitting forward motion to the toy and a train of gears for transmitting motion in a reverse direction.

65 2. A toy automobile including a body, wheels and axles to carry the body, a spiral spring constituting the power element, a

gear train for transmitting power to drive the toy in a forward direction, another train of gears consisting of an idler gear for transmitting motion such that the toy will move in a reverse direction, an automatic 70 gear shift operated by the driving spring, and means for locking the forward motion gear train in operative relation with the rear driving axle.

3. A toy automobile including a driving 75 axle, separate gears on said axle, a driving shaft, a coil spring thereon, separate spaced gears also on said driving shaft, and means automatically controlled by the expansion of the said spring as it unwinds for shifting 80 the gears on the driving shaft into and out of engagement with those on the said axle.

4. A toy automobile including a driving axle having spaced gears thereon, an idler gear meshing with one of said gears, pro- 85 pelling means including a spring, a driving shaft, and spaced gears mounted on said shaft, and means actuated by the unwind- ing of said spring for causing said shaft to be shifted in the direction of its axis to 90 cause the gear thereon meshing with the primary gear on the axle to shift out of en- gagement therewith, and the other gear on said shaft to engage with said idler.

5. A toy automobile including an axle, a 95 forward gear on said axle, a reverse gear also on said axle and spaced from the for- ward gear, an idler meshing with the re- 100 verse gear, and means for driving said axle through the gears including a shaft, a spring for rotating said shaft, spaced gears on said shaft for engaging at proper intervals the forward and reverse gears on the axle, and means actuated by the unwinding of said 105 spring for causing the shifting of the said shaft.

6. A toy automobile including an axle, a forward gear on said axle, a reverse gear also on said axle and spaced from the for- 110 ward gear, an idler meshing with the reverse gear, and means for driving said axle through the gears including a shaft, a spring for rotating said shaft, spaced gears on said shaft for engaging at proper in- 115 tervals the forward and reverse gears on the axle, and means for shifting said shaft including an abutment thereon, a spring po- 120 sitioned to exert its influence upon said abutment, and a shiftable stop element hav- 125 ing one end engaging with the abutment on the shaft to maintain the spring which en- gages therewith under compression, and also having an extension disposed in the path of movement of the spring which drives the shaft, to be engaged by the said spring when unwinding.

7. A toy automobile including a driving axle, forward and reverse gears mounted in spaced relation on said axle, an idler mesh- 130 ing with said reverse gear, a shaft arranged

parallel to the driving axle and having thereon gears spaced apart but arranged closer together than the gears on the driving axle, a spring for rotating said shaft, a device for maintaining said shaft in such a position that one of the gears thereof is initially in mesh with the forward gear of the axle, and means controlled by the movement of the spring for releasing said device to 10 permit the same to cause the shifting of the

shaft whereby the other gear of the latter may mesh with the idler associated with the reverse gear of the axle.

In testimony whereof we affix our signatures in the presence of two witnesses.
